BRACELET CHAIN CONSTRUCTION

Eugen Prestinari, Summit, N. J., assignor to
Gemex Company, Union, N. J.

Application November 20, 1947, Serial No. 787,072

3 Claims. (Cl. 59—80)

1

This invention relates to a flexible bracelet chain construction and is a continuation in part of my copending application Serial No. 752,127, filed June 3, 1947, now abandoned.

One of the objects of this invention is to provide a flexible bracelet chain construction of the type in which the links are arranged in staggered relationship. Another object is to provide a construction of the above character which may be made from inexpensive materials and with a minimum of manufacturing processes. Another object is to provide a bracelet chain of the above construction which will be durable and pleasing in appearance. Another object is to provide a bracelet chain of the above construction whose assembly may be accomplished by standard machine operations. Another object is to provide a bracelet chain of the above construction which is well suited for mass production methods of manufacture. Other objects will be in part obvious and in part pointed out hereinafter.

The invention accordingly consists in the features of construction, combinations of elements, arrangements of parts and relation and order of each of the same to one or more of the others, all as will be illustratively described herein, and the scope of the application of which will be indicated in the following claims.

In the accompanying drawing in which is shown one of the various possible embodiments of this invention:

Figure 1 is a top plan view of the bracelet chain as assembled;

Figure 2 is a fragmentary perspective view of a portion of one of the cross links;

Figure 3 is a perspective view of one of the connecting links or ornamental members prior to assembly;

Figure 4 is a perspective view of one of the ornamental members used on the sides of the bracelet chain;

Figure 5 is an enlarged top plan view of a small section of the bracelet chain during assembly;

Figure 6 is an enlarged vertical section of a portion of the bracelet chain taken along the line 6—6 of Figure 5;

Figure 7 is an enlarged vertical section of a portion of the bracelet chain taken along the line 7—7 of Figure 5; and

Figure 8 is an enlarged vertical section of a portion of the bracelet chain taken along the line 8—8 of Figure 6.

Similar reference characters refer to similar parts throughout the several views of the drawing.

2

Referring now to the drawing in detail, the bracelet chain, generally indicated at 10, includes a series of box-like connecting links generally indicated at 11 and a series of box-like ornamental members generally indicated at 12, all arranged in staggered relationship and interconnected in a manner to give desired flexibility to the chain.

Turning now to Figure 5, the bracelet chain includes a series of flat frame-like cross links, generally indicated at 13, which are flexibly interconnected by the connecting links 11 and also have secured thereto at various points therewith the ornamental members 12. Thus the cross links 13 which are arranged in alignment act as a foundation for the bracelet and due to the flexibility of the interconnection, the bracelet chain will quickly assume the shape of the wrist of the wearer.

The cross links 13, as shown in Figures 2 and 5, are in the form of a narrow rectangular frame and comprise longitudinal sides 14 and end portions 15 with upwardly extending tongue portions 9 formed thereon. The projections 16 extend from the sides of the cross links 13 at the end portions thereof. Additionally, the links have intermediate cross bars 17 connecting the longitudinal sides at regularly spaced intervals along the length. Projections 18 extend from the longitudinal sides 14 of the cross links opposite the cross bars 17. The cross links 13 are laid side by side in alignment, as shown in Figure 5, in position to be interconnected by the connecting links 11.

As shown in Figure 3, the connecting links 11 preferably have dome-shaped tops 19, sides 20 and ends 21. Prior to assembly, the ends 21 of the connecting links project from the body of the links to form the extensions or tongues 21a which later form the bottoms of the links after assembly, as will be described. The sides 20 of the connecting links have cut-out portions or notches 20a divided by a central projecting portion 20b forming shoulders 20c adjacent the extensions 21a in the same plane with the bottom edges of the central projecting portions 20b.

The ornamental members 12 used along the sides of the bracelet chain are very similar in construction to the connecting links 11, as shown in Figure 4. Thus, these ornamental members have top portions 22, sides 23 and 24 and ends 25. Like the connecting links, the ends 25 of the ornamental members have extensions or tongues 25a projecting from the body of the members to later form the bottom portion thereof, as will be

described. The inner side 23 of the ornamental members 12 includes cut-out portions or notches 23a separated by a central projecting portion 23b. The shoulders 23c of side 23 are in the same plane as the bottom edges of the side 24 and the central projection portion 23b.

To assemble the bracelet chain, the cross links 13 are laid side by side in alignment, as shown in Figure 5, and, next, the connecting links 11 are laid upon the long sides 14 of adjacent pairs of cross links with the extensions or tongues 21a extending through and beyond the bottom faces of the cross links. Ornamental members 12 are laid on the short ends 15 of the cross links 13 with the sides 24 thereof extending over the ends of the cross links and the extensions or tongues 25a adjacent the projections 16. In this position the central projecting portions 23b of the ornamental members extend into the cross links between the sides 14 thereof and against projections 9 and ends 15. Furthermore, the sides 14 of the cross links extend into the cut-out portions 23a of the ornamental members.

Connecting links 11 are also used in the bracelet chain for ornamental purposes and to hold and maintain the connecting links in spaced relationship in the position described above. Thus, connecting links 11 fit over the cross links immediately above the cross bars 17. When in position, these links 11 completely cover the cross bars 17 while the sides 14 of the cross links fit within the cut-out portions 20a. The ends 21 of these links fit over projections 18 of the cross links with the extensions 21a extending beyond the bottom faces of the cross links.

With all of the parts in the position described above, the extensions 21a and 25a of the links 11 and the ornamental members 12 are crimped over to form the bottoms of these parts and, hence, assume the positions more clearly shown in Figures 6, 7 and 8. More particularly, in this position, as shown in Figures 7 and 8 the extensions 21a are bent toward each other so that they rest on the shoulders 23c and the bottom edges of the projecting portions 20b. Likewise, as shown in Figure 6 the projections 25a of the ornamental members 12 are bent toward each other to rest against the shoulders 23c, the bottom edges of sides 24 and the bottom edges of projecting portions 23b. Thus projections 9 rest against sides 23 to hold the ornamental members against lateral movement relative to the cross-links. This completes the assembly of the bracelet and it will be noted that the links 11 now permanently connect the long sides 14 of adjacent pairs of cross links. The links 11 adjacent the cross bars 17 of the cross links as well as the ornamental members 12 on the ends of the cross links are permanently secured in position.

The exact position of the parts as finally assembled is shown most clearly in Figures 6, 7 and 8. Considering Figure 6 first, it will be seen that the sides 24 of the ornamental members 12 face outwardly to form the outer edges of the bracelet chain and the extensions 25a in their final position rest against the bottom sides of the end portions 15 of the cross links. The cut-out portions 23a of the sides 23 of the ornamental members fit over the sides 14 of the cross links. Accordingly, the ornamental members 12 are firmly secured in position.

Turning now to Figure 7, the links 11 can be seen in the positions they occupy for connecting purposes. Thus, the adjacent sides 14 of pairs of adjacent cross links extend through the cut-

out portions or notches 20a of the sides of the connecting links and the central projection portions 20b are disposed therebetween. The ends 21a, having been bent into their final position, 5 form the bottoms of the connecting links and are adjacent the bottom surfaces of sides 14.

The links 11 fitting over the cross bars 17 and projections 18 of the cross links 13 assume the positions shown in Figure 8. Thus, the cross bars 17 and projections 18 occupy the entire 10 interior lengths of the links 11. The central projecting portions 20b extend down over the opposite sides of the cross bars 17 and the extensions 21a form a base for the cross bars.

15 The tops of the links 11 and the ornamental members 12 may conveniently be dome-shaped and have the same dimensions so that all of these parts will be similar in appearance when assembled in the bracelet, as seen in Figure 1. Thus, 20 the bracelet chain assumes the appearance of a series of dome-shaped links arranged in staggered relationship but pivotally interconnected to achieve necessary flexibility. Furthermore, 25 the bracelet chain may be easily assembled by fixing a series of cross links in the position shown in Figure 3, slipping the links 11 and the ornamental members 12 into position and bending the bottoms into the final desired position as described.

30 It will thus be seen that there has been provided a thoroughly practical construction and method in which the several objects above referred to are successfully accomplished.

35 As many possible embodiments may be made of the mechanical features of the above invention and as the art herein described might be varied in various parts, all without departing from the scope of the invention, it is to be understood that all matter hereinbefore set forth or shown in the 40 accompanying drawing is to be interpreted as illustrative and not in a limiting sense.

What is claimed is:

1. A flexible bracelet chain comprising a series 45 of flat cross links each in the form of a narrow generally rectangular frame having long sides and short ends with at least one intermediate bar extending across the frame from one long side to the other, said cross links being arranged side-by-side extending transversely with respect to 50 the length of the chain with their ends at the sides of the chain, box-like connecting links pivotally connecting the long sides of adjacent cross links in the chain, each connecting link having a top, sides, ends and tongues extending from 55 said ends, the sides having notches receiving the portions of the long sides of adjacent cross links between the ends and the intermediate bars thereof, the tongues being bent under the long sides of the cross links to close the connecting 60 links, members substantially identical with the connecting links mounted on the cross links concealing the intermediate bars thereof, said bars being received between the sides of said members, the tongues of the latter being bent under the 65 cross links, the long sides of the cross links being received in the notches in the sides of said members.

2. A flexible bracelet chain comprising a series 70 of flat cross links each in the form of a narrow generally rectangular frame having long sides and short ends with at least one intermediate bar extending across the frame from one long side to the other, said cross links being arranged side-by-side extending transversely with respect 75 to the length of the chain with their ends at the

sides of the chain, box-like connecting links pivotally connecting the long sides of adjacent cross links in the chain, each connecting link having a top, sides, ends and tongues extending from said ends, the sides having notches receiving the portions of the long sides of adjacent cross links between the ends and the intermediate bars thereof, the tongues being bent under the long sides of the cross links to close the connecting links, members substantially identical with the connecting links mounted on the cross links concealing the intermediate bars thereof, said bars being received between the sides of said members, the tongues of the latter being bent under the cross links, the long sides of the cross links being received in the notches in the sides of said members, and additional members substantially identical with the connecting links with the exception that only one of the sides thereof has notches mounted on the cross links concealing the ends of the cross links, said ends of the cross links being received between the sides of said additional members and the tongues of the latter being bent under the cross links, the notches in the one side of said additional members receiving the long sides of the cross links.

3. A flexible bracelet chain comprising a series of flat cross links each in the form of a narrow generally rectangular frame having long sides and short ends with at least one intermediate bar extending across the frame from one long side to the other, said cross links being arranged side-by-side extending transversely with respect to the length of the chain with their ends at the sides of the chain, box-like dome-shaped connecting links pivotally connecting the long sides of adjacent cross links in the chain, each connecting link having a top, sides, ends and tongues extending from said ends, the sides having

notches receiving the portions of the long sides of adjacent cross links between the ends and the intermediate bars thereof, the tongues being bent under the long sides of the cross links to close the connecting links, dome-shaped members substantially identical with the connecting links mounted on the cross links concealing the intermediate bars thereof, said bars being received between the sides of said members, the tongues of the latter being bent under the cross links, the long sides of the cross links being received in the notches in the sides of said members, and additional dome-shaped members substantially identical with the connecting links with the exception that only one of the sides thereof has notches mounted on the cross links concealing the ends of the cross links, said ends of the cross links being received between the sides of said additional members and the tongues of the latter being bent under the cross links, the notches in the one side of said additional members receiving the long sides of the cross links.
